UNITED STATES PATENT OFFICE.

ARTHUR H. HAPPE AND WILLIAM J. KEEF, OF DETROIT, MICHIGAN, ASSIGNEES TO THE MICHIGAN STOVE COMPANY, OF DETROIT, MICHIGAN, A CORPORATION OF MICHIGAN.

ELECTRIC HEATING ELEMENT.

1,174,252.

Specification of Letters Patent.

Patented Mar. 7, 1916.

Application filed June 17, 1915. Serial No. 34,565.

To all whom it may concern:

Be it known that we, ARTHUR H. HAPPE and WILLIAM J. KEEF, citizens of the United States of America, residing at Detroit, in the county of Wayne and State of Michigan, have invented certain new and useful Improvements in Electric Heating Elements, of which the following is a specification, reference being had therein to the accompanying drawings.

This invention relates to armored electric heating elements and more particularly to such as have been especially designed for an electric cooking range.

The armored element, *per se*, is constructed with a view to securing maximum heat delivery with a minimum warping action, and with the parts thereof assembled whereby the core winding or element, which is the only destructible part thereof, can be easily and quickly removed and another winding element substituted. The armored element is self contained and capable of operating as a single element or of being associated with other elements to form a grid or heating surface of a required area.

When the armored element is used in connection with the cooking top of a range, its size and shape are conducive to close arrangement in a grid with its wiring fully protected from anything that may boil over on the range. Should it become impaired, however, any armored element can be bodily removed, repaired and replaced.

The armored element possesses many characteristics that will be apparent as the structural details are reviewed, and reference will now be had to the drawings, wherein—

Figure 1 is a perspective view of an armor case; Fig. 2 is a similar view of an upper sheet of insulation; Fig. 3 is a similar view of a resistance heating element; Fig. 4 is a similar view of an intermediate sheet of insulation; Fig. 5 is a similar view of a sectional blade contact conductor, or member; Fig. 6 is a similar view of a support of insulation; Fig. 7 is a similar view of a lower sheet of insulation; Fig. 8 is a similar view of a retaining pressure plate; Fig. 9 is a similar view of wedging cleats or bars; Fig. 10 is a longitudinal sectional view of the armored heating element showing all the parts illustrated in Figs. 1 to 9 inclusive, assembled; Fig. 11 is a cross sectional view taken on or about the line XI—XI of Fig. 10;

Fig. 12 is a perspective view of a portion of the resistance heating element shown in Fig. 3, showing a connector partly installed; Fig. 13 is a side elevation of the armored element forming part of a grid for an electric cooking range; Fig. 14 is a plan of a boiling grid partly broken away; Fig. 15 is a cross sectional view of a portion of the grid taken on or about the line XV—XV of Fig. 13; Fig. 16 is a perspective view of a spring clip connector; Fig. 17 is a plan of the cooking top of an electric range partly broken away; Fig. 18 is a plan of an oven or boiler grid partly broken away; Fig. 19 is a longitudinal sectional view of the same partly in elevation taken on or about the line XIX—XIX of Fig. 18; Fig. 20 is a cross sectional view taken on or about the line XX—XX of Fig. 18; Fig. 21 is an enlarged longitudinal sectional view of an armored tandem element adapted for an oven or broiler grid, and Fig. 22 is a diagrammatic view illustrating the tandem arrangement of the armored element.

In describing our invention by aid of the views above referred to, it is thought best to refer to the manner of assembling the parts of the armored element, describe each part in its order, and then consider the element as associated with other elements in forming the grids for an electric cooking range.

The armored element comprises a metallic box shaped case 1, having end walls 2 and longitudinal side walls 3, said side walls having oppositely disposed inclined slots 4 with the inclination of the slots of one wall the reverse of the slots of the other wall. In this armor case is placed an upper sheet of insulation 5, as shown in Fig. 2, said sheet of insulation covering the whole flat inside surface of the case. Placed against this upper sheet of insulation is a resistance heating element, as shown in Fig. 3, said element comprising a flat core of insulation 6, such as mica, said core having each end thereof provided with a set of openings 7. Wound upon the core is a resistance ribbon or wire 8 having the ends thereof extending through the openings 7 of the core to form loops, whereby tongues 9 of connectors 10 can be bent around the looped ends of the resistance windings. The tongues 9 are wrapped around that portion of the resistance windings depending from the openings 7 and can be soldered or pressed into close

contact to insure a positive electrical connection. The connectors 10 are made of thin nickel or other material of high heat resistance and said connectors are bent inwardly 5 upon the under side of the element and formed with depending positioning tongues 11. The element is smaller than the inside of the armor case 1 to maintain its edges out of contact with the walls of the case and 10 thus prevent short circuits.

An intermediate sheet of insulation 12, shown in Fig. 4 is now placed against the resistance winding with the ends of said 15 sheet of insulation extending between the connectors 10 and the end convolutions of the winding. The sheet of insulation 12 is the same width and length as the upper sheet of insulation 5 and has its ends provided with rectangular notches 12^a the same 20 width as the connectors 10 to provide clearance for the connectors. In this manner the sheet of insulation 12 can cooperate with the sheet of insulation 5 in laterally centering the resistance winding in the armored 25 case.

Next to the intermediate sheet of insulation 12 is placed a sectional blade contact member, comprising blade sections 13 and a 30 filler section 14 (which, by extending the blade sections, may be left out). The blade sections 13 are duplicates turned end for end, each having the inner end thereof slotted and the material between the slits bent down to form a blade 15. The sections 35 13 and 14 are provided with eyelet openings 16, best shown in Fig. 5, and the sections are held in position by a support 17, in the form of a sheet of insulation shown in Fig. 6. This sheet of insulation has openings 18 40 adapted to register with the openings 16 and receives eyelets 19. The sheet of insulation 17 also has oblong openings 20 providing passage for the blades 15 and the positioning tongue 11 of the terminals 10. 45 With the positioning tongues 11 extending into the oblong openings 20 of the support 17, the resistance heating element is properly sandwiched between the upper and intermediate sheets of insulation 5 and 12, and 50 with the edges of these sheets engaging the walls 3 of the case 1, it is impossible for the resistance heating element to accidentally shift and contact with the walls 3 of the case.

55 On the insulation support 17 is placed a lower sheet of insulation 21 corresponding in size to the upper sheet of insulation 5. The lower sheet of insulation 21 has oblong openings 22 providing passage for the blades 15 and the positioning tongues 11 and said sheet of insulation 21 insulates the eyelets 19 relative to a metallic retaining pressure plate 23 which is next placed in the case. 60 This retaining plate corresponds in area to 65 the case 1 and has large rectangular open-

ings 24 providing clearance for the blades 15 and the positioning tongues 11. To hold this retaining plate within the case a plurality of wedging cleats or bars 25 are employed. These wedging cleats are placed in 70 the inclined slots 4 of the walls 3 and swung or rotated to force and bind all of the parts shown in Figs. 2 to 8 inclusive in the case shown in Fig. 1. Each wedging cleat or bar contiguous to the ends thereof has a de- 75 pressed portion or protuberance 26 engaging the inner sides of the walls 3 and preventing accidental displacement of the cleats after having been properly seated. In rotating or swinging the cleats into position the ends of 80 the cleats ride up on the inclined walls of the slots 4 and become wedged therein, said cleats bringing sufficient pressure to bear upon the metallic retaining plate 23 as to bind all of the parts in correct relation 85 within the case 1. The slots may be made parallel to the surface of the case in which instance an outside pressure is brought to bear at various points on the pressure plate when the cleats may be slipped in and will 90 hold when the outside pressure is removed.

To prevent an armored element from being tampered with or disassembled without detection, we fill the slots 4 with a 95 cement of high heat resistance and of a color similar to the armor case. This cement is designated 4^a in Figs. 10 and 11.

With the various parts assembled as shown in sections, Figs. 10 and 11, it is to be noted that the blade sections 13 of the 100 blade member have a full contact with the connectors 10 and by placing the ends of the intermediate sheet of insulation 12 between the connectors and the end convolutions of the resistance winding, an electric current is 105 caused to pass through the end convolutions, thereby utilizing the complete winding for heating purposes.

Considering now the armored heating element as a component part of a range heating grid, such as can be advantageously used in the cooking top of the electric cooking range disclosed by an application filed Dec. 26, 1914, Serial No. 879,215, in the name of William J. Keep, reference will be 110 had to Figs. 13 to 17 inclusive. The grid comprises a rectangular frame having flat apertured bars 27 connected by bridge pieces 28 and these bridge pieces are connected by supports 29 in parallelism with the bars 27, 115 but in a higher plane. The upper edges of the supports 29 are provided with sets of spacing lugs 30. These lugs are adapted to extend into the case of an armored element, against the end walls 2 of the case and correctly position the armored heating elements in parallelism upon the supports 29. We attach considerable importance to this manner of mounting the heating elements, 120 insomuch that the elements are not fastened 125 130

at their ends and elongation of the elements can take place. By allowing such expansion and elongation of an element it precludes buckling or warping. Then again, an armored element can be easily removed for renewal purposes.

At the corners of the grid are depending positioning lugs 31 engaging in a range structure 33 and with the frame supported 10 in this manner, the armored heating elements of the supports 29 have the heating surfaces thereof in a plane slightly above that of the cooking top 34 of the range structure, as best shown in Fig. 13.

15 Connected to the apertured bars 27 of the frame by screw bolts 35, nuts 36, and washers of insulation 37 are a plurality of inwardly projecting brackets 38. The brackets 38 are thoroughly insulated from 20 the bars 27 and said brackets extend inwardly beneath the supports 29 below the ends of the heating elements. There are two brackets for each armored heating element and said brackets are provided with 25 spring clip connectors adapted to receive the blade contacts 15 of the heating element. Each spring clip connector is in the form of two resilient contact arms 39 swiveled on the brackets, and between which a blade contact 30 is adapted to extend and establish an electric circuit through a heating element, a set of brackets and screw bolts holding the brackets. The screw bolts 35 are connected in series by connectors 40 and lead wires 41 35 are connected to the terminal screw bolts 35, as shown in Fig. 17.

The resilient spring clip connectors permit of expansion and contraction of the heating elements and no weight whatsoever is sustained by the brackets 38, as the walls 3 of the armored heating element cases rest upon 40 the supports 29, consequently the heating elements are capable of sustaining considerable weight.

45 In operation, a current flows through the blade contacts 15 of each element, through connectors 10 and through the resistance winding 8. All of these parts are thoroughly insulated from the case 1, as are the retaining plate 23, cleats 25, eyelets 19 and metallic parts not intended as conductors.

In Figs. 18 to 22 inclusive there is illustrated a tandem heating element and by the novel construction resorted to we have found 50 that heating elements can be made of considerable length and advantageously used in various structures. The heating element is armored and is constructed upon the same principle as the armored heating elements 55 previously described. In this instance, however, we use channel cases 50 disposed in longitudinal alignment and devoid of end walls. In each case and insulated therefrom is a heating element 51 and connecting the 60 heating elements is an intermediate contact

conductor 52 extending out of one case into the other. Associated with said contact conductor are end contact conductors 53 which extend out of the cases and have angularly disposed apertured terminals 54. 70 The contact conductors 52 and 53 are riveted or otherwise connected to a sheet or sheets of insulation and are retained in engagement with the heating element 51 by a sheet of insulation 55 and a pressure 75 plate 56, said pressure plate being held within the cases 50 by transverse cleats or bars 57. With the pressure plate 56 of a length greater than the combined length of the cases 50, the pressure plate serves 80 in both cases and constitutes a connecting medium between the cases, whereby the armored element can be easily handled. The pressure plate 56 has depending ends 85 58 constituting positioning lugs when the armored element is used in connection with an oven or broiler grid, such as illustrated in Figs. 18 to 20 inclusive.

An oven or broiler grid comprises channel side bars 59, a channel rear bar 60, a solid front bar 61, and an inverted channel brace 62 connecting the front and rear bars of the grid. The channel side bars 59 and the brace 62 support the armored tandem heating elements. The ends of the cases 90 50 of each element rest upon the brace 62 and the inner side walls of the channel bars 59. The depending positioning lugs 58 of the pressure plate 56 of each element engage the inner sides of the inner walls of the bars 59, as best shown in Fig. 19, thereby 95 correctly positioning the elements. With the outer ends of the cases 50 open, the terminals 54 of each heating element can extend into the channel side bars 59 and some of the terminals 54 are provided with connectors 63 placing the heating elements in series. The channel side bars 59 afford 100 protecting conduits for leading in wires which are carried through a hollow trunnion 64 forming part of the rear channel bar 60.

The channel side bars 59 are provided 105 with covers 65 and the rear channel bar 60 with a cover 66, the ends of which overlap the ends of the covers 65. The inner edges 110 of the covers 65 have extensions or branches 67 overlying the ends of the heating elements, and all of said covers and extensions thereof are shaped to deflect and shed liquid or foreign matter that may be deposited upon the heating elements. The covers 65 and 66 are retained in position by swiveled 115 clamps or buttons 68 and 69, the former being on the front bar 61 and the latter upon webs or corner pieces 70 at a juncture of the side and rear bars 59 and 60. A further liquid shedding cover 71 is placed over the confronting ends of the cases 50 of the heating elements, said cover having one end 120 125 130

thereof provided with a tongue 72 extending under a lip 73 on the inner wall of the rear bar 60, and the opposite end of the cover is held by a swiveled clamp or button 74 on the front bar 61. We attach considerable importance to this central cover as it protects the confronting ends of the cases 50 and prevents liquid or foreign matter from entering the ends of the cases.

10 In connection with the single and tandem heating elements we have discovered a metallic armor which is free from injury by constant and ordinary use, thereby increasing the longevity of elements, and this discovery forms the subject matter of an application filed June 4th, 1915, Serial No. 32,107 in the name of William J. Keep.

15 We attach considerable importance to the compactness of the armored heating element, the manner in which it is supported, and the ease with which it may be installed. This is an important factor in the manufacture of electric cooking ranges and the heating elements herein described are a salient feature of the Keep electric cooking range heretofore referred to.

20 We find that out of curiosity our armored elements have been dismounted and reassembled with some of the sheets of insulation left out, probably because their usefulness was not apparent. We wish to have a central station man or a competent electrician replace an element if necessary, but our guarantee does not cover displacement 25 by incompetent or curious persons. We have therefore made a cement of high heat resistance and of the color of the armor case which we press into the slots and which hardens in a few hours and acts as a seal.

40 What we claim is:—

1. A case, a heating element within the case and insulated therefrom, and transverse cleats wedged in the side walls of said case for retaining said elements 45 therein.

2. A case having side walls provided with inclined slots, a heating element in said case and insulated therefrom, transverse cleats having the ends thereof in the 50 slots of said case walls, and means on said cleats adapted to prevent displacement of said cleats relative to said case.

3. A case, a core in said case, a resistance ribbon on said core, connectors at the ends 55 of said ribbon, a support of insulation in said case, blade sections carried by said support of insulation and contacting with said connectors, retaining plates in said case, and means engaging in the walls of said case adapted to hold said retaining plates in said case with the above mentioned elements under pressure therein.

60 4. A case, a core in said case, a resistance ribbon on said core, a retaining plate in said case provided with openings, blades

extending through the openings of said retaining plate, and connectors between said blades and the ends of said resistance ribbon.

5. In a case, a core, a resistance ribbon on 70 said core, a retaining plate provided with openings, blades extending through the openings of said retaining plate, connectors between said blades and the ends of said resistance ribbon, means transversely of 75 said retaining plate to hold the above mentioned element under pressure in said case.

6. In an armored heating element for electric cooking and heating grids, a case, a resistance winding in said case and insulated therefrom, a retaining plate in said case, blade contact members between said retaining plate and said resistance winding insulated from said retaining plate and having electrical connection with the ends 80 of said resistance winding, and detachable means adapted to hold said retaining plate in said case.

7. In an armored element for electric cooking and heating grids, a case composed 90 of an inverted box with slots in its side, a heating element consisting of a wire wound on a core of insulation, insulation between the element and said case, a pressure plate in said case pressed against the insulation 95 and the element, and cross clamping bars engaging in the slots of said inverted box adapted to retain said pressure plates therein.

8. An armored electric heating element 100 for a range grid composed of a metal case having slots in its depending sides, a sheet of insulation on the inside of said case, the heating element having a winding positioned equidistant from the wall of said 105 case, a sheet of insulation against the winding of said element, connectors bent over said last sheet of insulation, metal conductors fixed on a support of insulation and pressed against said connectors, a sheet of 110 insulation, a pressure plate, and bars in said slots to clamp all parts together in said case.

9. In an armored electric heating element for a range grid, a case, an insulated element in said case, a pressure plate fitted in 115 said case, and bars holding said pressure plate in said case and extending through the walls thereof.

10. An armor for a heating element of 120 a grid range, comprising a case, a heating element in said case, means for closing said case, and a seal of heat-proof cement for said closing means adapted to show said case has been opened.

11. In a range, a case for a heating element thereof, a heating element in said case, said case having slots in the walls thereof adapted to accommodate closing means for said case, and a seal of heat- 130

proof cement in said slots by which tampering with the closing means of said case may be detected.

12. Armored elements placed end to end, 5 rigid metallic conducting pieces connecting the confronting ends of said armored elements, and covers for such metallic conducting pieces.

13. A heating element for electric cooking and heating grids, comprising cases disposed end to end, a resistance winding in each of said cases, means common to all of said cases for maintaining said resistance windings under pressure in each case, and 15 a cover for the confronting ends of said cases.

14. A heating element comprising cases disposed end to end, a resistance winding in each of said cases and insulated therefrom, said resistance winding having projecting contacts, a cover for the confronting ends of said cases, and covers for the projecting contacts of said resistance winding.

25 15. A heating element composed of windings disposed end to end, a rigid flat connector for the confronting ends of said windings, contacts projecting from the outer ends of said windings, independent 30 sheets of insulation connecting said connectors to said contacts, and means throughout the length of said element confining

said connectors and said contacts under pressure.

16. Heating strip elements placed end to 35 end, a metallic armor for said elements, and metallic connectors within said armor connecting the confronting ends of said elements.

17. A heating element for electric cooking and heating grids, comprising elements composed of resistance windings disposed end to end, connectors at the ends of said resistance windings, a case for said elements, and means within said case common 45 to said elements for maintaining said resistance windings under pressure.

18. A heating element composed of combined resistance windings disposed end to end, connectors for said resistance windings, projecting contacts for said element, independent sheets of insulation connected to and maintaining said connectors and contacts in a plane parallel with said resistance windings, and covers confining said 55 resistance windings and said connectors.

In testimony whereof we affix our signatures in presence of two witnesses.
